UNITED STATES PATENT OFFICE.

HARRY E. ASBURY, OF PHILADELPHIA, PENNSYLVANIA.

HAND-GRENADE.

1,311,740.

Specification of Letters Patent. Patented July 29, 1919.

Application filed June 15, 1917. Serial No. 174,890.

To all whom it may concern:

Be it known that I, HARRY E. ASBURY, a citizen of the United States, residing in Philadelphia, Pennsylvania, have invented 5 certain Improvements in Hand-Grenades, of which the following is a specification.

My invention relates to hand grenades, and consists of certain improvements in grenades of the type set forth in my prior applications, filed February 18, 1916, Serial 10 Nos. 79,139, and 79,140; and the object of my present invention is to provide a hand grenade with an improved form of releasing mechanism for the firing pin, and an improved form of fuse holder; the latter being 15 arranged to vent freely to the atmosphere and avoid all danger of accidental explosion due to defective fuses.

These and other features of my invention 20 are more fully described hereinafter, reference being had to the accompanying drawings, in which:

Figure 1, is a sectional view on the line I—I, Fig. 2.

Fig. 2, is a sectional plan view on the line II—II, Fig. 1.

Fig. 3, is a sectional plan view on the line III—III, Fig. 1.

Fig. 4, is a sectional plan view on the line 30 IV—IV, Fig. 1.

Fig. 5, is an elevation, partly in section, showing the firing pin released, and

Fig. 6, is an inverted plan view of the grenade illustrating a detail of my invention.

In the drawings, 1 represents, on a slightly 35 enlarged scale, the shell of a hand grenade of suitable size and weight, which may be made of cast metal, iron or steel, as may be desired, which shell is preferably scored or 40 grooved externally, as indicated at 2 and 3 in the several views, so that upon bursting, due to explosion of any contained charge, the shell will be separated into a large mass 45 of fragments. This shell is provided with a loading opening 4, normally closed by a screw plug 5, which may be disposed at any convenient point, but preferably about the middle of the shell and at a point opposite the position of the detonating cap, as herein- 50 after described.

Within the shell a casing 6 is mounted, having a chamber 7 for the reception of a firing pin 8, to which motion may be transmitted by a coiled spring 9 when the firing 55 pin is released; such spring being normally

compressed and retained between a fixed part of the grenade and a shoulder 10 on said firing pin by means hereinafter described.

Within the shell, shoulders 12 and 13, are 60 provided at opposite ends of the same, and in engagement with these shoulders are plates 14 and 15; the plate 14 being confined to the casing 6 by displacing the metal of the latter with respect to said plate 14, while 65 the plate 15 is held to the casing 6 by means of a collar 16 threaded into said casing at 17 and having a shoulder 18 bearing upon said plate 15. The casing thus held is disposed substantially centrally with respect to the 70 main shell.

The ends of the shell are closed by caps 19 and 20. The cap 19 is provided with an opening 21, and interposed between said cap and the plate 14 is a block 22, to which a 75 fuse 23 is secured and which leads into a detonating cap 24. Said block also receives an anvil member 25 threaded into the block, as indicated at 26; said anvil member receiving a primer cap 27 and engaging at the 80 bottom a corrugated washer 28, which confines the split end of the fuse to a seat 29 in said block 22. This arrangement of anvil member and the manner of securing the split end of the fuse in place therein is substantially 85 similar to that disclosed in my prior application, Serial No. 79,140; said anvil member being provided with grooves 30, serving as vents.

It will be noted that a complete wall of 90 metal lies between the anvil member in which the primary cap is exploded, and the fuse leading to the detonating cap. I also prefer to interpose a metal washer 31 between the block 22 and the plate 14 to prevent 95 absolutely all danger of gases passing from the casing 6 to the fuse or the detonating cap when the primer cap is exploded. This metal washer may be set in a recess 33 in the block 22, if desired.

The block receiving the time fuse is open, as indicated at 22^a, in line with the opening in the closing plug of the shell in order that any defect in a fuse which might cause a preliminary explosion or blow-out, may 105 pass directly to the atmosphere without endangering the life of the person about to hurl the grenade. Normally, this space will be filled with a suitable waterproofing material, such as paraffin, wax or the like, indi- 110

cated at 34, sufficient to protect the fuse from dampness or moisture but not preventing proper venting of the fuse in case defects should cause it to blowout at any point 5 between the split end held between the anvil member and the block 22, and the detonating cap.

In order to position the block 22, the plate 14 is preferably provided with a guiding pin 10 35, and said block may be apertured at 36 for the reception thereof.

The cap 20 at the opposite end of the shell, which is threaded into the same and contacts with the plate 15 is provided centrally 15 with a movable member 38, normally arranged with other means to be described, for holding the firing pin in the inactive position; such position being inward with respect to said cap 20, and the member 38 20 being held in place by a safety catch in the form of a pin 39 having a head 40 engaging the flange 41 of said member 38 against the action of a spring 42 tending to withdraw 25 said safety pin. Prior to use, the safety pin 39 is retained in position by a cotter pin 43, passing through the cap 20 and which may engage the shouldered head 40 of said pin 39 in the manner indicated in the drawings.

For the purpose of holding the firing pin 30 8 out of action, balls 45, which may be of the usual anti-friction type common to ball bearings, are interposed between a rounded groove 46 adjacent the end of the firing pin and an inclosing wall 47 carried by the movable member 38. As long as said member is held in the position indicated in Fig. 1, with the safety pin 39 in place, the firing pin 8 will be held in the inactive position. When the safety pin 39 is released, which 40 45 may be accomplished by removing the cotter pin 43 and then slightly depressing the movable member 38, to permit displacement of the head 40 of said pin 39, the grenade is ready to be fired, and upon the release of the finger from said member 38 in the act of throwing the grenade, it will be forced outwardly by a spring 48 adapted to an internal recess of the same and confined between the same and said firing pin. This action 50 55 removes the inclosing wall 47 for the balls holding the firing pin in the inactive position so that the spring 9 can come into action; the balls being thrown to one side and the firing pin being forced into contact with the primer cap 27 which ignites the fuse in the usual manner to explode the charge.

Within the chamber of the shell of the grenade, the explosive material is placed, and this may be in the form of a solid block 60 of explosive material, as indicated at 50, centrally apertured at 51 to receive the casing 6, and having a recess 52 adjacent the aperture but not passing entirely through the block to accommodate the detonating 65 cap. This recess should be long enough to

accommodate the longest cap and therefore the greatest timing possible in the use of this structure.

Any suitable explosive material may be employed, whether capable of being molded 70 into blocks such as described or not, and in the space surrounding the explosive material, or with the same, I propose to introduce slugs, balls, shells or other suitable material in order that additional missiles 75 may be provided upon the explosion of the grenade.

I claim:

1. In a hand grenade, the combination with a shell having a detonating cap, a firing 80 pin, and means for actuating said firing pin, of a plurality of balls in engagement with said firing pin, an outwardly movable member having a wall inclosing said balls, a spring for actuating said movable member 85 to release the ball, locking means for said movable member, and means for automatically releasing said locking means.

2. In a hand grenade, the combination with a shell having a detonating cap, a firing 90 pin, and means for actuating said firing pin, of a plurality of balls in engagement with said firing pin, an outwardly movable member having a wall inclosing said balls whereby the same may hold the firing pin inactive, 95 a spring for actuating said movable member to release the balls; said movable member having a flange, a locking bolt in engagement with the flange of said movable member, and means for automatically releasing 100 said locking bolt.

3. In a hand grenade, the combination with a shell having a detonating cap, a firing pin, and means for actuating said firing pin, of removable closures for the ends of said 105 shell, one of said closures being apertured, a recessed block located within the apertured closure, and a time fuse carried by the block within its recess; said fuse being carried by said block in position open to the 110 atmosphere through the apertured closure whereby complete venting of defective ignition of such fuse may be effected.

4. In a hand grenade, the combination with a shell having a detonating cap, a firing 115 pin, and means for actuating said firing pin, of removable closures for the ends of said shell, one of said closures being apertured, diaphragms or plates separating the chamber of the grenade for an explosive 120 charge from said closures, a block interposed between the apertured closure and one of said plates, and a time fuse carried by the block; said fuse being carried by the block in position open to the atmosphere 125 through the apertured closure whereby complete venting of defective ignition of such fuse may be effected.

5. In a hand grenade, the combination with a shell having a detonating cap, a fir- 130

- ing pin, and means for actuating said firing pin, of removable closures for the ends of said shell, one of said closures being apertured, diaphragms or plates separating the space for the explosive charge from said 5 closures, a block interposed between the apertured closure and one of said plates, a time fuse, said block adapted to receive the end of said time fuse and being open to the aperture in the closure whereby complete venting of defective ignition of such fuse may be effected, and moisture-proof means for inclosing the exposed portion of said 10 time fuse.
- 15 6. In a hand grenade, the combination with a shell having a detonating cap, a firing pin, and means for actuating said firing pin, of removable closures for the ends of said shell, one of said closures being apertured, diaphragms or plates separating the space for the explosive charge from said 20 closures, a block interposed between the apertured closure and one of said plates, a time fuse, said block adapted to receive the end of said time fuse and being open to the aperture in the closure whereby complete venting of defective ignition of such fuse may be effected, removable means for securing the ignition end of said time fuse in 25 place, a percussion cap carried thereby, and moisture-proof means for inclosing the exposed portion of said time fuse.
7. In a hand grenade, the combination with a shell having a detonating cap, a firing pin, and means for actuating said firing pin, of removable closures for the ends of said shell, one of said closures being apertured, diaphragms or plates separating the space for the explosive charge from said 35 closures, a block interposed between the apertured closure and one of said plates, a time fuse, said block adapted to receive the end of said time fuse and being open to the 40 aperture in the closure whereby complete venting of defective ignition of such fuse may be effected, and a sealing washer disposed between the block and the adjacent diaphragm or plate.
8. In a hand grenade, the combination with a shell having a detonating cap, a firing pin, and means for actuating said firing pin, of removable closures for the ends of said shell, one of said closures being apertured, diaphragms or plates separating the space for the explosive charge from said 45 closures, a casing for the firing pin disposed between said diaphragms or plates, a block interposed between the apertured closure and one of said plates, a time fuse, said block adapted to receive and retain the end 50 of the time fuse and being open to the aperture in the closure whereby complete venting of defective ignition may be effected, and a solid block of explosive material apertured for the passage of the casing inclosing 55 the firing pin and recessed to receive the detonating cap.
9. In a hand grenade, the combination with a shell having a detonating cap, a firing pin, and means for actuating said firing pin, of removable closures for the ends of said shell, one of said closures being apertured, diaphragms or plates separating the space for the explosive charge from said closures, a block interposed between the apertured 60 closure and one of said plates, a time fuse, said block adapted to receive the end of the time fuse and being open to the aperture in the closure whereby complete venting of defective ignition may be effected, and the diaphragm adjacent thereto being apertured 65 for the passage of the detonating cap, and means for positioning said block with respect to said diaphragm.

HARRY E. ASBURY.
